UNITED STATES PATENT OFFICE.

SAMUEL O. NATIONS, OF SNYDER, TEXAS.

DESIGN FOR A CASING FOR COMPUTING DEVICES.

Application filed April 4, 1927. Serial No. 21,447. Term of patent 14 years.

To all whom it may concern:

Be it known that I, SAMUEL O. NATIONS, a citizen of the United States, and a resident of Snyder, in the county of Scurry, and State of Texas, have invented a new, original, and ornamental Design for a Casing for Computing Devices, of which the following is a specification, reference being had to the accompanying drawing, forming part thereof.

Figure 1 is a top plan view of a casing for computing devices, showing my new design.

Figure 2 is a side elevation thereof.

I claim:

The ornamental design for a casing for computing devices, as shown.

SAMUEL O. NATIONS.
